A. W. NELSON.
SASH SUPPORTER.
APPLICATION FILED JULY 5, 1921.

Patented Dec. 5, 1922.

Patented Dec. 5, 1922.

UNITED STATES PATENT OFFICE.

ARTHUR W. NELSON, OF WILLIAMSPORT, PENNSYLVANIA.

SASH SUPPORTER.

Application filed July 5, 1921. Serial No. 482,431.

To all whom it may concern:

Be it known that I, ARTHUR W. NELSON, a citizen of the United States, residing at Williamsport, in the county of Lycoming 5 and State of Pennsylvania, have invented certain new and useful Improvements in Sash Supporters; and I do declare the following to be a full, clear, and exact description of the invention, such as will enable others skilled in the art to which it appertains to make and use the same.

This invention relates to improvements in means for supporting window sashes and it has for one of its objects to provide a simple 15 and inexpensive article of the character hereinafter described which will obviate the necessity of employing cords and weights to retain the sashes in the various positions to which they have been moved.

The principal object of the invention is to generally improve upon my patented sash 20 supporter bearing the Number 1,127,666, the same having been granted to me on February 9, 1915. A careful review of this 25 patent will disclose the fact that it embodies a plurality of brackets carrying rollers contacting the bottoms of the usual guide channels in which the sash slides, the rollers being so associated with the brackets that they 30 are permitted to automatically assume an angular position after the sash has moved downward a predetermined distance, causing the latter to shift bodily in a lateral direction and frictionally bind against one of 35 the guide strips and in this way holding the sash in the various positions to which it has been moved.

Actual use of the supporting means disclosed in the above named patent, has disclosed the fact that the construction is such 40 that the rollers do not, in many instances, become canted and the desired result is not effectively accomplished.

In view of the foregoing circumstances, 45 the present invention contemplates employing a plurality of attaching brackets and rollers which are such that the brackets are permitted to move vertically with respect to the rollers and after moving a predetermined distance downward, the rollers engage inclined stops with which the brackets 50 are provided, thus positively insuring that they will become angled or canted so as to shift the sash against the desired guide strips, thereby holding the sash in various 55 elevated positions and overcoming any pos-

sibility of it slipping or accidentally dropping unless caused to do so by force.

Other objects and advantages of the invention will be apparent during the course 60 of the following description.

In the accompanying drawings forming a part of this specification and in which like numbers are employed to designate like parts throughout the same:

Figure 1 is an elevational view of a conventional type of window frame and sash equipped with my improved supporting means.

Figure 2 is an enlarged sectional view taken substantially on the plane of the line 2-2 of Fig. 1.

Figure 3 is an elevational view of one of the vertical edges of the sash showing the rollers in their normal horizontal position.

Figure 3^a is a similar view showing a portion of the sash and one of the rollers in the inclined position that it takes when the sash moves downwardly.

Figure 4 is a detail view of one of the 80 brackets.

Figure 5 is a section taken substantially on the plane of the line 5-5 of Fig. 4.

In the drawings I have shown a conventional type of window frame F including 85 the usual fixed vertical guide channels G. A sash S is slidably mounted in these guide channels.

In carrying out the invention, I form upper and lower spaced notches 1 in the opposite vertical edges of the sash and secure in 90 these notches, attaching brackets 2. While these brackets may be constructed otherwise, I prefer to form each one from a strip of 95 spring metal which is bent upon itself as indicated at 3, one of the bent portions 4 being formed with holes 5 for passage of the fastenings 6 which serve to secure the brackets to the sash as is obvious. It is to be noted 100 that this portion 4 has its lower free end directed laterally outward as indicated at 7 thus forming a stop which is inclined downwardly as shown. The opposite free end of the strip is spaced away from the sash and is bifurcated to form a pair of spaced arms 105 8, the lower ends of which extend below the stop 7 and have their extremities bent upwardly and upon themselves to form bearings 9. As before indicated, the improved 110 sash supporting means in addition to these brackets, embodies a plurality of rollers which are designed to frictionally engage the

bottoms of the guide channels to retain the sash in the various elevated positions to which it has been moved. These rollers are here indicated by the numeral 10 and they 6 include oppositely disposed short axles 11 which are rotatably received in the bearings 9. Here, I wish to direct attention to the fact that the bearings are such that they permit the rollers to move freely upward with 10 respect to the brackets, that is, when the sash has been elevated and starts to move downwardly. It is of course obvious that when the sash does move down in this manner and the rollers remain stationary, until 15 they come into contact with the inclined stops 7 and are automatically canted, thus accomplishing the end sought. It is also to be pointed out that, since the brackets are constructed from spring metal and the arms 20 8 are disconnected from the sashes, they tend to spring outwardly and keep the rollers in contact with the bottoms of the guide channels at all times. With this construction and arrangement, it will be seen that the rollers 25 must necessarily become angled or canted, thus overcoming the possibility of the sash dropping a considerable distance without being forced into frictional contact with one of the guide strips of the aforesaid guide 30 channels:

Consideration of the foregoing description taken in connection with the drawings would probably be sufficient to enable persons skilled in the art to obtain a clear understanding of the invention. However, a brief review of the operation of the improved invention may well be reviewed here. To this end, it will be seen that when the sash S is raised, the pintles or axles of the rollers 10 40 will assume horizontal positions and will thus allow the sash to be easily and readily raised. When, however, the sash is released, its own weight will cause it to move downwardly. The rollers being held in frictional contact with the bottoms of the channels by the resilient arms 8 will remain substantially stationary, that is, they will not move up or down, but will rotate, of course. This being the case, the brackets 2 will be carried 45 downwardly with the sash and in so doing, the inclined stops 7 will come into contact with the rollers 10 and cant the latter so that they will assume the position indicated in Fig. 3^a. It is obvious that when the rollers 50 take this inclined or canted position, they will shift the sash bodily into frictional contact with one of the guide strips which constitutes a part of the aforesaid guide channels, thus retaining the sash in any one of 55 the positions to which it has been moved. It is understood, of course, that the frictional contact between the sash and guide strip is not sufficiently great to prevent the sash being lowered when gripped and pulled 60 down by force.

Since probably the best results may be obtained with the construction and arrangement herein shown and described, this is taken as the preferred embodiment of the invention. However, slight minor changes 70 coming within the scope of the subjoined claims may be resorted to.

I claim:

1. The combination with a fixed guide and sash slidably mounted therein; of a roller 75 carried by the sash and vertically movable with respect thereto, and separate and independent means for positively canting the roller after the sash has moved downwardly a pre-determined distance, whereby the sash 80 is shifted bodily into engagement with one of the guide members and held frictionally against further downward movement.

2. The combination with a fixed guide and a sash slidably mounted therein; of a roller 85 carried by the sash and vertically movable with respect thereto, and a transversely disposed inclined stop with which said roller is designed to engage at a pre-determined time, said stop serving to positively incline or cant 90 the roller transversely with respect to its axis, whereby to bodily shift the sash against one of the guides to frictionally engage therewith and to prevent further downward movement of the sash.

3. The combination with a window frame 95 including guide channels and a sash slidably mounted in said channels; of an attaching bracket secured to one vertical edge of the sash, said bracket including bearings, a roller 100 including axles journaled in the latter, being vertically movable with respect to said bracket, and a horizontally inclined abutment carried by the latter for positively canting the roller when the sash moves 105 downward.

4. The combination with a window frame including fixed guide channels and sash slidably mounted in said channels; of an attaching bracket secured to one of the vertical 110 edges of the sash, said bracket being composed from a strip of spring metal secured to and having its lower free end spaced from the vertical edge of the window, said lower end being bifurcated to form a pair of arms, 115 the extremities of which are bent upwardly and upon themselves to provide bearings, a roller including axles journaled in the latter, being vertically movable with respect to said arms, and means for positively canting the 120 roller when the sash has moved downwardly a predetermined distance.

5. The combination with a window frame including opposed vertical fixed guide channels and a sash slidably mounted in said 125 channels; a plurality of brackets secured to the opposite vertical edges of the sash, each bracket being composed from a single strip of spring metal bent upon itself to form an attaching portion, said portion having its 130

lower free end bent laterally outward and angled to provide an inclined stop, the opposite free end of said strip being bifurcated to provide a pair of spring arms, the extremities of the latter being bent upwardly and upon themselves to form open bearings, and a plurality of rollers including axles journaled in the bearings of said brackets, said rollers being positively canted when the sash moves downwardly a predetermined distance and brings the inclined stops into engagement therewith.

6. A retaining device for a window sash comprising a roller designed for disposition between the guide strips of a window frame, mounting means for said roller, said mounting means permitting free movement of the roller with respect to the sash, and including means for positively canting the roller in a

manner to shift the sash bodily against one of the guides to frictionally engage the sash therewith.

7. In a retaining device for window sashes, a bracket designed to be secured to one of the vertical edges of the sash, said bracket being formed from a single strip of spring metal bent upon itself to form an attaching portion, said portion having its lower free end bent laterally outward and angled to provide an inclined stop, the opposite end of said strip being bifurcated to form a pair of open bearings, and a roller having axles rotatable in said bearings, said roller being engageable with and canted by said stop.

In testimony whereof I have hereunto set my hand.

ARTHUR W. NELSON.
